CHEMICAL APPLICATOR

Alexander H. Gore, Chicago, Ill.

Application August 24, 1953, Serial No. 26,574

Term of patent 14 years

(Cl. D9—2)

To all whom it may concern:

Be it known that I, Alexander H. Gore, a citizen of the United States, residing at Chicago, county of Cook, Illinois, have invented a new, original, and ornamental Design for a Chemical Applicator, of which the following is a specification, reference being had to the accompanying drawing, forming a part hereof.

Figure 1 is a plan view;

Figure 2 is a side view;

Figure 3 is a front view, illustrating the bristle portion;

Figure 4 is a rear view, illustrating the absorbent applicator; and

Figure 5 is a cross-sectional view taken along line 5—5 of Figure 1, illustrating the ridge con-

figuration in the handle portion, of a chemical applicator showing my new design.

I claim:

The ornamental design for a chemical applicator, as shown and described.

ALEXANDER H. GORE.
